UNITED STATES PATENT OFFICE.

ANDREW EDMON JESTER, OF JESTER, TENNESSEE.

GATE-LATCH.

SPECIFICATION forming part of Letters Patent No. 349,350, dated September 21, 1886.

Application filed August 9, 1886. Serial No. 210,436. (No model.)

To all whom it may concern:

Be it known that I, ANDREW EDMON JESTER, a citizen of the United States, residing at Jester, in the county of Chester and State of Tennessee, have invented certain new and useful Improvements in Gate-Latches; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to fastening devices for gates, and is designed most particularly for that class which close automatically when opened in either direction, and has for its object the construction of a simple, cheap, and durable latch or fastening which will be economical in manufacture, simple, effective, easily operated either by hand or foot, and not liable to get out of repair.

The improvement consists in the simple and novel construction more fully hereinafter described and claimed.

In the drawings, Figure 1 is an elevation of a gate and its posts with the latch applied thereto; Fig. 2, a partial section on the line X X; Fig. 3, a section on the line Y Y.

The gate A is supported between the posts B B' in any known way, so as to open in either direction. It is hinged to the post B' in such manner that it will close automatically by gravitating, preferably by the means shown in an application filed by me simultaneously with this. To the side of the post B adjacent the end batten of the gate is secured a stop, C. It consists, preferably, of a strip of metal bent approximately U-shaped, and having flanges c, by which it may be secured to the post. These flanges may project in or out, and is a matter of convenience. However, it is preferred to have them extend in toward each other, as shown, as thereby a smooth unbroken outline is preserved. The stop may be of any desired configuration other than that shown, and I do not wish to confine myself or be limited to such.

The gate is provided with an oscillating latch, D, which consists of a plate or casting, d, pivoted between its ends, and provided with arms d', to embrace the sides of the stop and

hold the gate closed. It is located near one end of the stop, so it may be readily disengaged by partially rotating it, which will free 55 one of the arms and permit the gate to be opened, which when closing will cause the arm opposite to that previously released to engage with a side of the stop and rotate the latch and bring the arm previously disengaged into its first position or engagement with the stop on a side opposite to that struck by the arm of the latch. A shaft, E', mounted horizontally in the gate batten and bracket secured to one of the pickets, has the latch 60 mounted on its outer end, and a cross-bar, E, on its inner end, which is adjustably held in place on said shaft by a set-screw, e. By removing the set-screw the cross-bar may be removed together with the latch and shaft. The 65 cross-bar extends in the same horizontal plane as the latch when the gate is closed, and may be grasped and used as a means for rotating the shaft and disengaging the latch. For greater convenience operating-rods F are pivotally attached to the ends of the cross-bar, and extend downward within convenient reach of the feet, and terminate in outwardly-curved and flattened or expanded ends f, which afford a purchase for the feet. The rods are held from 70 swinging about by keepers g. Their upper ends curve inward sufficiently far to permit a quarter-revolution of the shaft and latch in each direction from a horizontal position. By this means the latch is prevented from turning 75 too far. In the operation of the latch the rods come in contact with the shaft, thereby limiting the movement, as and for the purpose just stated.

The operation of the device can be readily 80 understood from the foregoing, reference being had to the drawings; but it may be well to observe that the latch can be rotated by simply pressing down upon one of the arms 85 equally as well as by pressing with the feet upon the pedestal or curved ends f of the operating-rods. The disposition of the latch relative to the end of the stop is immaterial, so long as it is close to the end. It is preferable to have the corners about which the arms of 90 the latch work slightly rounded, to prevent binding and give a greater movement. It is also preferable to have the latch work about the closed end of the stop, as thereby it is 95 100

prevented from getting between the two limbs in case said stop be made of flat metal and bent as shown.

The parts may be reversed without departing from the spirit of my invention. The stop may be applied to the gate and the pivoted latch to the post; but such construction is not desirable.

Having thus described my invention, what I claim, and desire to secure by Letters Patent, is—

1. The combination, with the post and gate, of a stop secured to the one and projecting some distance from its face, and an oscillating latch secured to the other, composed of a base-plate having arms extended from each end at right angles thereto and parallel with the axis of the latch for engaging the sides of the stop, substantially as shown and described.
2. The combination, with the post and gate, of the stop consisting of a strip of metal bent approximately U shape, and having flanges projecting from its edges, and the oscillating latch composed of a base-plate having arms projected from each end at right angles there-

to and parallel with the axis of the latch, and adapted to embrace the sides of the stop, substantially as shown, and for the purpose described.

3. The combination, with the post and gate, of the stop, the oscillating shaft, the latch secured to its outer end, the short cross-bar secured to the inner end, and the operating-rods attached to each end of said bar and extended within convenient reach of the feet, substantially as and for the purposes set forth.

4. The combination, with the stop and the shaft having the latch on one end and the cross-bar on the other, of the operating-rods secured to the ends of the cross-bar, and curved inward at their upper ends and outward at their lower ends, substantially as and for the purpose described.

In testimony whereof I affix my signature in presence of two witnesses.

ANDREW EDMON JESTER.
